Attorneys

UNITED STATES PATENT OFFICE.

THOMAS DAVENHALL, OF MOOSIC, PENNSYLVANIA.

REINFORCED CONCRETE STRUCTURE.

Application filed April 14, 1922. Serial No. 552,772.

To all whom it may concern:

Be it known that I, THOMAS DAVENHALL, a citizen of the United States, residing at Moosic, in the county of Lackawanna and 5 State of Pennsylvania, have invented certain new and useful Improvements in Reinforced Concrete Structures; and I do hereby declare the following to be a full, clear, and exact description of the invention, such as 10 will enable others skilled in the art to which it appertains to make and use the same.

This invention relates to reinforced concrete columnar structures particularly adapted to posts or shores to be used in 15 mines.

The object of the invention is to produce a post, shore or the like, sufficiently light to be easily handled, of strong and rigid construction, and having metallic caps on 20 its ends providing protective surfaces to be engaged by wedges driven between an end of a post or prop and a ceiling, wall, floor or other structure engaged or shored thereby.

25 The invention consists in the reinforced and capped structure more specifically described hereinafter, illustrated in the drawings and defined in the appended claims.

In the drawings:

30 Figure 1 is a longitudinal section through one end of a post or prop, made in accordance with my invention;

Figure 1^a is an elevation of the end of a post opposite that shown in Figure 1;

35 Figure 2 is an elevation of a metallic cap member adapted to be embedded in the concrete at one end of the post and to cover the extreme end of the post;

Figure 3 is a plan view of the cap;

40 Figure 4 is a section on the line 4—4 of Figure 1 looking in the direction of the arrows;

Figure 5 is a section on the line 5—5 of Figure 1 looking in the direction of the arrows;

45 Figure 6 is an elevation on a small scale of a post or prop made in accordance with this invention;

Figure 7 is a top plan view of a modified 50 form of cap;

Figure 8 is an under plan view of the cap shown in Figure 7;

Figure 9 is a longitudinal section through 55 the end of a post having the modified cap applied, taken on line 9—9 of Figure 7;

Figure 10 is a longitudinal section through

the end of a post having the modified cap, on line 10—10 of Figure 7;

Figure 11 is a cross section on line 11—11 of Figure 9;

Figure 12 is a cross section on line 12—12 of Figure 10, and

Figure 13 is a longitudinal section of a prop end illustrating a third form of cap.

Like reference characters indicate like 65 parts throughout the several views.

The embodiment illustrated is a reinforced concrete columnar structure that is round in cross section and tapered slightly from the center toward each end. It will 70 be understood, however, that the particular form of the structure in cross section, its degree of taper, or whether tapered at all, is a matter of design; and that the structure may be square or of other polygonal form 75 in section or of any suitable cross section that will not interfere with the ready handling of the structure or diminish its strength.

In Figures 1 to 6, the article as a whole, 80 which I choose to call a post, is designated by the letter P and tapers from the middle toward each end to a slight degree, the diameter being greater at the point 1 than elsewhere. The main body of the post comprises a mass of concrete 2 preferably but not necessarily having an opening 3 from 85 end to end therethrough imparting to the post lightness without materially diminishing its strength. The said opening 3 also 90 has a function in the manufacture of the post in that it enables the concrete to set and dry more quickly.

At each end of the post is a metallic cap 4 comprising a hollow tubular body 5, an 95 inner flange or transverse anchoring means comprising arms 6 and an outer flanged cap plate 7. The radiating anchoring arms 6 of the inner flange are provided with openings, notches or other seats 8 in their 100 ends for a purpose to be presently described. The cap plate 7 comprises a peripheral substantially cylindrical flange 9 extending backward toward arms 6; said flange 9 may have radial perforations 10 therein and is 105 intended to be flush with the exterior surface of the concrete of the post when anchored thereto. It will be understood that a similar cap 4 is provided at each end of the post thus providing a flat, metallic surface 110 on each end and a protection for the corners of the concrete by flange 9. The

tubular opening through each cap registers with the bore 3 extending from end to end of the post. There may be a plurality of openings 5^a (preferably three) in the wall 5 of the member 5, and a plurality of openings 7^a in the cap plate 7 to lighten the cap and permit concrete to enter for the purpose of more readily anchoring the cap member to the post. Embedded within the 10 concrete mass of the post is a plurality of angularly spaced rods or reinforcing bars 11, the ends of each bar fitting in notches or other seats 8 formed in the extremities of the arms 6 radiating from the lower or inner end of the tubular portion 5 of each cap. These reinforcing bars 11 are shown as of rectangular section but it will be obvious that they may be of any suitable section or may be irregular or twisted reinforcing 15 bars of any suitable known type. Embracing the bars 11 at spaced intervals throughout the length of the post are bands 12. The inner surfaces of said bands 12 contact with the outer sides of the bars and confine 20 them against springing outward, holding said bars in definite relation to each other while the concrete is being poured and strengthening the reinforcement. The reinforcing bars 11 may extend in parallel relation from cap to cap, if desired, in order 25 that rings of the same size may be used at intervals from end to end of the post to surround and stiffen the bars. In the construction shown there are six radiating arms 30 6 on each cap plate and six reinforcing bars 11. It will be obvious that larger or smaller numbers of bars may be used according to choice and the strength desired 35 to be imparted to the post.

40 In manufacturing this reenforced post, bars 11 of proper length will be provided, bands 12 properly spaced and secured at suitable distances apart encircling the bars, and the cap members 4 set up with the ends 45 of the bars or rods seated in the notches 8 at the extremities of the radiating arms 6. After setting up the framework the concrete may be poured in the mold which is given a shape the counterpart of that desired for 50 the post. The holes 5^a laterally through the tubular part 5 of the cap permit the concrete to flow into them and thus assist in anchoring and steadyng the caps on the post. The concrete will also press into the 55 holes 7^a and 10 of each cap and give further security to the cap as well as lightening the structure without unduly weakening it.

The modified cap 4^a illustrated in Figures 60 7 to 12 inclusive is designed for large and strongly reenforced posts or columns. It is constructed substantially like the cap 4 except that anchoring lugs or arms 6^a project 65 radially inward from the edge of the flange 9^a and have seats 8^a for the reception of additional reinforcing bars 11^a. Said lugs

or arms 6^a are spaced so as to extend midway between or to bisect the angles between arms 6. Thus, as shown, twice the number of reinforcing bars may be embedded in a post having this form of cap 4^a as compared 70 with the number that can be applied with the first described form of cap 4. The bands 12 surround the bars 11 and 11^a, confining and reinforcing them. The bars 11^a extend nearly to the ends of the post, midway between the bars 11 and alternating with them. 75

In Figure 13 is illustrated a cap 4^b adapted for small or light posts. This form of cap comprises no central tubular extension but has the flange 9^b and the radiating lugs or arms 6^b provided with seats 8^b for the reception of the ends of reinforcing bars 11^b. Bands 12 are used to encircle the reinforcing bars 11^b the same as in the other forms. 80

The procedure to be followed in making posts is substantially the same with each form of cap. The particular cap selected depends upon the size of the post to be made and the strength required. 85

In use the posts or props may be erected bearing against opposed surfaces to be stayed or braced and wedges driven between said surfaces and the metallic faces of the cap plates on the ends of the posts thus 90 setting them firmly in place and wedging it rigidly in contact with the ceiling or walls designed to be supported by the posts. The construction is sufficiently light and strong and may be conveniently handled in the uses 100 for which it was designed.

Having described my invention what I claim and desire to secure by Letters Patent is:

1. A reenforced concrete post comprising 105 a mass of concrete, a protecting cap anchored to one end thereto, said cap having anchoring means embedded in the concrete and provided with seats, and a plurality of embedded reinforcing bars the ends of 110 which engage said seats.

2. A reenforced concrete post comprising a mass of concrete having a cap anchored thereto at one end providing an outer protective cap plate, said cap having anchoring means embedded in the concrete and provided with seats, a plurality of reinforcing bars the ends of which engage said seats, and a plurality of bands surrounding said bars, said bars and bands being embedded 115 in the concrete. 120

3. A reenforced concrete post comprising a concrete body having a longitudinal opening therein, a cap anchored to said concrete at one end and having an opening there-through registering with the opening in the post, said cap providing a protective cap plate on the extremity of the post and having anchoring means embedded in the concrete and provided with seats, reinforcing 125 130

bars the ends of which engage said seats, and bands embracing said bars at spaced intervals, the bars and bands being embedded in the concrete.

5 4. A reenforced concrete post comprising a concrete mass having an opening longitudinally therethrough; a metallic cap, having openings registering with the opening in the concrete mass, and including protective cap plates, and anchoring means provided with seats embedded in the concrete; a plurality of reinforcing bars the ends of which engage said seats in the anchoring means, and reinforcing bands embedded in 10 the concrete embracing said bars.

15 5. A cap for reenforced concrete posts, said cap comprising a cap plate and anchoring means of less diameter than the cap plate extending transverse of the axis of the 20 cap, said anchoring means having seats for reinforcing bars.

25 6. A cap for reenforced concrete posts, said cap comprising a cap plate having a peripheral substantially cylindrical flange and radiating anchoring means adapted to be buried in the concrete, said anchoring means having seats for the reception of reinforcing bars.

30 7. A cap for reenforced concrete posts, said cap comprising a cap plate having a peripheral substantially cylindrical flange, anchoring means projecting radially inward from said flange and provided with seats for reinforcing bars.

8. A cap for reenforced concrete posts, 35 said cap comprising a cap plate having a peripheral substantially cylindrical flange, anchoring means projecting radially inward from said flange and provided with seats for reinforcing bars, and a central member 40 having anchoring means extending radially outward therefrom, said last named anchoring means being provided with seats for reinforcing bars.

9. A cap for reenforced concrete posts 45 comprising a tubular part having on one end a cap plate with a peripheral cylindrical flange and on the other end radially extending anchoring arms of less radius than the cap said arms provided with outwardly directed seats adapted to receive reinforcement bars.

50 10. A cap for reenforced concrete posts comprising a tubular part having on one end a cap plate with a peripheral cylindrical 55 flange and anchoring arms extending radially inwardly from said peripheral flange and outwardly from the other end of the tubular member, said inwardly and outwardly extending arms arranged angularly 60 so as to alternate successively and provided on their free ends with seats adapted to receive reinforcement bars, substantially as specified.

65 In testimony whereof I affix my signature.

THOMAS DAVENHALL.
